United States Patent Office.

JOHN FARREL, OF NEW YORK, N. Y.

Letters Patent No. 76,898, dated April 21, 1868.

IMPROVEMENT IN FIRE-PROOF SAFES.

The Schedule referred to in these Letters Patent and making part of the same.

TO ALL WHOM IT MAY CONCERN:

Be it known that I, JOHN FARREL, of the city, county, and State of New York, have invented a new and useful Improvement in the Construction of Fire-Proof Safes; and I do hereby declare that the following is a full, clear, and exact description of the same, reference being had to the accompanying drawings, making part of this specification, in which—

Figure 1 is a front view of the safe, with the door open.

Figure 2, a vertical section, at the line A a, of fig. 1, with the door closed; and

Figure 3 a horizontal section, at the line B b, of fig. 2.

The same letters indicate like parts in all the figures.

As heretofore constructed, the frame of the door of fire-proof safes, and the front casing thereof, into which the door fits, have been formed each of one plate or piece of wrought or cast iron; but experience has proved that this plan of construction is very objectionable, for the reason that the junction of the edges of the door with the front iron casing of the safe forms a good conducting-surface to convey heat to the inside of the safe.

The object of my invention is to overcome this difficulty, and the nature of my invention consists in making the iron frame of the door, and the front iron casing of such safes, each of two or more plates of iron, and securing between each of said plates a non-conducting substance, to prevent the conveyance of heat from the outside to the inside of the safe.

In the accompanying drawings, *a* represents the inner shell of the safe, the front side of which is formed with the usual opening for the reception of valuables, and the front edge formed with a square flange all around it, as at *b*. To the outer face of this flange is fitted any suitable non-conducting substance, *c*, such as a strip of felt, wood, cork, cloth, flannel, or any other poor or non-conducting material, and then the inner edge, *c'*, of the front casing of the outer shell *d* is secured to the flange *b*, with the non-conducting material interposed, by means of screw-bolts, which pass into ears or lips *e*, cast on to the said inner edge of the front casing, leaving a considerable portion of the non-conducting material exposed, as shown in the drawings.

The door *f* is hung in the usual way, and is also formed of two separate pieces of iron, lettered *g* and *h* in the drawings. The inner edge of the outer plate *g* is formed all around with a suitable flange, *i*, and to this flange is fitted another strip, of any suitable non-conducting substance, *j*, and then one edge of the plate *h*, forming the inner half of the door, is secured to the flange *i*, with the non-conducting material interposed, by means of screw-bolts, which pass into ears *k*, cast on the inner side of the plate *h*, leaving much of the non-conducting material exposed.

It will be seen from the drawings that, when the door of the safe is shut, the surfaces of the non-conducting material in the front casing and in the door are in close contact, and this interposition of the non-conducting substance between the door and outer casing of the safe effectually breaks the conducting-power of the iron to the inside of the safe, and, consequently, adds greatly to the security of its contents.

I do not wish to confine myself to making the front casing of the safe and the door each of two plates or pieces of iron, with an interposed non-conducting material, as it will be obvious that the door and front casing of the safe may be made of more than two pieces of iron, and that any good non-conducting substance may be interposed between them.

Having thus fully described my invention, what I claim therein as new, and desire to secure by Letters Patent, is—

Constructing the front casing and the door of fire-proof safes each of two or more plates of iron, with a non-conducting substance interposed between the several plates, substantially as described, and for the purpose set forth.

JOHN FARREL.
